COOLING TOWER

John L. Goldsmith, Houston, Tex., assignor to Hudson
Engineering Corporation, Houston, Tex., a corporation
of Texas

Filed Nov. 7, 1961, Ser. No. 67,407

Term of patent 14 years

(Cl. D62—4)

The FIGURE is a perspective view of a cooling tower embodying my new design.

The other side and end of the cooling tower, not shown, are substantially like the side and end shown in the single figure of the drawing.

I claim:

The ornamental design for a cooling tower, as shown and described.
